AUXILIARY SEAL AND MEASURE FOR
COLLAPSIBLE TUBES

William A. Mulford, Gladwyne, Pa.

Application March 5, 1935, Serial No. 9,405

2 Claims. (Cl. 221—60)

The object of my invention is to provide an auxiliary seal and measure for collapsible tubes such as are used for pastes, fluids, liquid or semi-liquid substances, such as glue, tooth paste, and the like.

More specifically, my invention consists of a collapsible tube having at one end thereof a nipple formed with an outlet opening therethrough, a disk mounted outside the tube and adjacent the end of said nipple, and a rod of irregular outline supporting said disk for reciprocating movement toward and away from said outlet but retaining said disk against rotation relative to said outlet.

For a further exposition of my invention, reference may be had to the annexed drawing and specification, at the end thereof my invention will be specifically pointed out and claimed.

In the drawing:

Fig. 1 is a side elevation, with parts in longitudinal cross-section, and with the seal and measure in open position.

Fig. 2 is a side elevation, with parts in longitudinal cross-section, with the cap in position, and with the seal and measure in closed position.

Fig. 3 is a perspective view of the seal and measure before its application to a collapsible tube.

In that embodiment of my invention chosen for illustration in the drawing and description in the specification, there is shown a collapsible tube 1 preferably of soft, bendable metal or alloy, although it may also be made of paper or similar bendable material. At one end tube 1 carries a nipple 2 having an outlet opening 3 therethrough, through which the contents of the tube 1 may be expelled as by squeezing on the opposite or closed end of the tube. Nipple 2 carries on its outer surface means, such as screw-threads 4, which operate with corresponding means to detachably retain a cap 5 in position so as to close opening 3.

My novel auxiliary seal and measure consists of a disk or like flat member 6, mounted opposite and adjacent the end of outlet 3 and adapted to be located within cap 5. Disk 6 is mounted upon a support 7 which is of irregular shape in cross-section, as, for example, the shape of a rectangle. At its inner end support 7 is bent over as indicated at 8, to co-operate with the inner end of nipple 2 and to provide disk 6 with a limited reciprocating movement toward and away from outlet 3. Owing to the irregular outline of support 7 and the corresponding hole in nipple 2 in which it is mounted, disk 6 is held against rotation relative to outlet 3.

The auxiliary seal and measure is conveniently

assembled on the tube 1 by passing the support 7 through the hole in the nipple 2, before the opposite end of tube 1 from nipple 2 is formed into the seal or closure. The inner end of support 7 is then bent over, as indicated at 8, to retain support 7 and the disk 6 supported thereon in position on the tube. 5

The operation of my device is quite simple. The cap 5 is removed and the contents of the tube or a part thereof are expelled through the outlet opening 3 by squeezing or collapsing the tube 1. The pressure of the contents flowing out of the opening 3 moves disk 6 outward away from the end of nipple 2. It will thus be seen that disk 6 acts as a guard or protector for the inner wall of cap 5. In the case of contents of a pasty nature, pressure of the contents passing through opening 3 forms a column or rod of the contents. When this column or rod has pressed disk 6 to its limit of outward travel on support 7, a definite amount of the contents lies between disk 6 and the end of nipple 2. This may then be removed and the cap 5 replaced by being located over disk 6, which is then pressed inward and cap 5 attached to screw-threads 4. It will thus be seen that disk 6 forms a measuring device.

I do not intend to be limited save as the scope of the prior art and of the attached claims may require.

I claim:

1. An auxiliary seal and measure for collapsible tubes comprising, in combination, a collapsible tube having a nipple at one end with an outlet opening therethrough, a disk of suitable size to cover said opening and the end of said nipple, and a support comprising a rod of irregularly shaped outline passing through a hole distinct from said outlet opening and of similar outline to said rod and located in said nipple and having its inner end bent for co-operation with the inner end of said nipple to provide said disk with limited reciprocating movement relative to the end of said nipple and to hold said disk against rotation relative to said nipple. 45

2. In combination with a collapsible tube having a nipple formed with an outlet therethrough, an auxiliary seal and measure comprising a flat member mounted for limited reciprocating movement toward and away from said nipple and held against either partial or complete rotation relative to said nipple, and a support for said member comprising a rod of irregular outline passing through a hole of similar outline in said nipple and having its inner end bent to form a stop. 50
